(57) **CLAIM**

The ornamental design for a display screen or portion thereof with icon, as shown and described.

DESCRIPTION

FIG. 1 is a front view of a display screen or portion thereof with icon, showing my new design; and,

FIG. 2 is a front view of a display screen or portion thereof with icon, showing an alternative embodiment of the new design.

The dot-dash broken lines illustrating portions of the display screen are included for the purpose of illustrating environmental structure and form no part of the claimed design.

1 Claim, 1 Drawing Sheet

FIG. 1

FIG. 2
